UNITED STATES PATENT OFFICE.

EDGAR S. SMITH, OF SHARON, PENNSYLVANIA, ASSIGNOR TO THE DAMASCUS BRAKE BEAM CO., OF CLEVELAND, OHIO, A CORPORATION OF OHIO.

FORGED-STEEL FULCRUM.

982,445.

Specification of Letters Patent. Patented Jan. 24, 1911.

Application filed May 2, 1910. Serial No. 558,988.

To all whom it may concern:

Be it known that I, EDGAR S. SMITH, a citizen of the United States, residing at Sharon, in the county of Mercer and State of Pennsylvania, have invented certain new and useful Improvements in Forged-Steel Fulcrums, of which the following is a specification.

The present invention has reference to 10 brake-beams of the forged metal type and has for its purpose to construct a brake-beam wherein the fulcrum member thereof may be securely attached to the compression member without in any manner distorting the latter, 15 or otherwise deflecting the brake-beam as a whole; and wherein the fulcrum part is secured to the tension member in a more simple and effective manner than heretofore proposed.

20 The arrangement herein set forth is designed with particular reference to that type of brake-beam known as the Waycott brake beam, and in the present instance is intended as a further improvement upon the brake-beams of that pattern disclosed in the co-pending applications Serial Nos. 546,665, 25 546,666 and 546,702 and all dated March 1, 1910.

Summarily stated the invention comprises 30 a reinforcing or bracing element associated with the fulcrum member and adapted to lie within the trough of the compression member immediately within that portion thereof embraced by the fulcrum, and in that 35 position to effectively resist the clamping incident to securing the fulcrum parts thereon; and to withstand the strain imposed on the strut to the extent that the compression member will retain its shape.

40 The invention is shown in its preferred embodiment and modifications thereof, in the accompanying drawings wherein:—

Figure 1 is a side elevation thereof with the compression member in section, Fig. 1^a 45 is an end view of the same, Fig. 2 is a top plan view, Fig. 3 shows the several parts disassembled, Fig. 4 is a side elevation of a modified structure, Fig. 5 is a top plan view thereof, Fig. 6 shows the parts disassembled, 50 and; Figs. 7 to 9 illustrate views corresponding to Figs. 3 to 6 respectively of a further modified structure.

Referring to the several views in further detail and with like characters designating 55 corresponding parts in the different figures,

1 indicates the fulcrum or strut which in itself comprises a two part forging 2; 3 is the usual compression member of the brake-beam, and 4 the tension member therefor. Said fulcrum sections 2 are each formed with a pinched portion 5 and 6, and intermediate those parts the fulcrum is expanded and slightly deflected for the mounting and operation of the brake lever all as substantially shown in the above mentioned applications.

The ends of the members 2 adjacent the pinched sections are designed with shoulders 7, and to overlie and partly embrace a section of the compression member 3 in substantially that manner shown in Figs. 1 and 1^a. To reinforce the connection between the fulcrum and the compression member and relieve the latter of the strain subjected thereto by the former, there is provided a 75 filler piece or block 8 which is disposed within the trough of the compression member immediately within that section thereof which is embraced by the engaging ends of the strut 1. The part 8 comprises a head 80 designed to conform to and contact with the compression member, and has shoulders 9 which lie in against the shoulders 7 of the strut sections. Said filler member is further formed with a web portion 10 which when the filler is in position lies intermediate the pinched parts 5 of the fulcrum and, in this 85 position afford the necessary means for spacing the fulcrum sections, as will be readily seen from Fig. 1.

The opposite end of the fulcrum or that part of the members thereof adjacent the pinched sections 6 is expanded as at 11 to receive the T beam or tension member 4 and the extreme ends of said parts 6 are disposed outwardly and in opposite directions in which relation they are secured against 95 said tension member as shown.

With the several parts assembled in the above described relation, they are secured 100 through the medium of the rivets 12 and 13.

In the arrangement shown in Figs. 4 to 6 the ends of the fulcrum parts which engage with the compression member are shaped to conform to the compression member, and are split to provide sections 14 which embrace said member. The cutaway portions intermediate the sections 14 provide tongues 15 which in co-operation are disposed inwardly 105 against each other and lie within and against 110

the compression member. Said tongues form in this instance the filler or reinforcing element for the strut, and for the spacing element thereof a block 16 is provided. In position said block 16 lies intermediate and against the pinched sections 5 as in the arrangement shown in Fig. 1. In all other respects the strut is constructed and secured in position similar to that shown and described in the above figure (Fig. 1) and need not therefore be further described here.

The arrangement shown in Figs. 7 to 9 is characteristic in that the fulcrum parts do not themselves embrace the compression member but instead form only the reinforcing or filler element for the compression member. As shown in the figure the ends of the fulcrum parts are provided with shoulders 17 and inwardly disposed parts 18, which parts 18 in coöperation constitute the reinforcing or filler block for said compression member. A clamping plate 19 overlies the compression member and has its end portions 19' secured to the fulcrum upon the pinched portions 20 of the latter. Said clamping plate 19 is formed with two shoulders 21 which lie immediately against the shoulders 17 of the strut sections. The spacing member in this construction consists of the block 22 which in position lies between the pinched sections of the fulcrum. In this relation the several parts are secured by the bolt 23. The connection between the fulcrum and the tension member is the same as that shown and described of the above figures.

While the illustrations herewith show the invention as applied to brake-beams made up of angle compression members and T-tension members the same method may with equal facility also be employed in fitting fulcrums or beams of U section, or other form of compression member having a channel open on the side toward the fulcrum.

45 I claim:—

1. In a trussed brake-beam, a tension member, a fulcrum comprising a two-part forging designed to conform to and embrace a section of the compression member of the beam, shoulders formed on said fulcrum

parts adjacent the compression member, and a reinforcing member secured to the fulcrum and constructed to lie within the embraced portion of the compression member and against the shoulders of the fulcrum parts, whereby to withstand the strain imposed upon said compression member by said fulcrum.

2. In a trussed brake-beam, a tension member, a fulcrum comprising a two-part forging each part whereof is formed with a pinched portion and a portion to embrace the compression member of the beam, a reinforcing block having a web portion, said block having its web portion secured to the pinched portion of the fulcrum parts, and lying within the embraced portion of the compression member whereby to withstand the strain imposed upon said compression member by said fulcrum.

3. In a trussed brake-beam, a tension member, a fulcrum comprising a two-part forging, each part whereof is formed with a pinched portion, a shoulder, and a part adapted to embrace the compression member of the beam; and a reinforcing block having shoulders and a web portion, said block adapted to lie within the embraced portion of the compression member with said shoulders against the shoulders of the fulcrum parts and the web portion intermediate the pinched portions of said fulcrum parts, and providing a spacing element for the latter.

4. In a trussed brake-beam, a tension member, a fulcrum comprising a two-part forging constructed at one end to embrace the compression member of the beam, and expanded and bent outwardly at the other end thereof for securement to the tension member, and a reinforcing member lying within the compression members and having a part providing a spacing element for the parts of the fulcrum member.

The foregoing specification signed at 9
Sharon, Pa., this 29th day of April, 1910.

EDGAR S. SMITH,

In presence of two witnesses:

MARY ADAMS,

W. A. MCKNIGHT.
